Patented Apr. 9, 1968

210,731

POWER SUPPLY UNIT FOR MAINTENANCE AND REPAIR OF ELECTRONIC EQUIPMENT

William J. Siegel, 814 E. Franklin Ave.,
Silver Spring, Md. 20901

Filed May 31, 1966, Ser. No. 2,481

Term of patent 14 years

(Cl. D26—15)

Fig. 1

Fig. 2

FIG. 1 is a front perspective view of a power supply unit for maintenance and repair of electronic equipment showing my new design; and

FIG. 2 is a side view thereof.

The back and base are substantially unadorned.

The broken lines are shown for illustrative purposes only.

The characteristic features of my design reside in the detailed arrangement of the front panel member, as best illustrated in FIG. 1.

I claim:

The ornamental design for a power supply unit for maintenance and repair of electronic equipment, shown and described.
